UNITED STATES PATENT OFFICE.

EMMA BOOBAR, OF MINNEAPOLIS, MINNESOTA.

CORSET WITH ABDOMINAL SUPPORT.

1,427,087.

Specification of Letters Patent. Patented Aug. 29, 1922.

Application filed December 24, 1919. Serial No. 347,158.

To all whom it may concern:

Be it known that I, EMMA BOOBAR, a citizen of the United States, residing at Minneapolis, in the county of Hennepin and State 5 of Minnesota, have invented certain new and useful Improvements in Corsets with Abdominal Supports; and I do hereby declare the following to be a full, clear, and exact description of the invention, such as 10 will enable others skilled in the art to which it appertains to make and use the same.

My invention has for its object to provide a combined corset and abdominal support of simple construction and which will be efficient for the several purposes hereinafter noted.

In this improved corset I obtain the abdominal support by the addition of but few and simple parts which do not in any sense 20 detract from the corset in its use as an ordinary corset.

The improved corset is illustrated in the accompanying drawings wherein like characters indicate like parts throughout the 25 several views.

Referring to the drawings:

Fig. 1 is a perspective view looking at one side of the corset;

Fig. 2 is a perspective view looking at the 30 front of the corset;

Fig. 3 is a rear elevation of the corset showing the same spread out flat; and

Fig. 4 is a fragmentary horizontal section taken approximately on the line 4—4 of 35 Fig. 3 showing the parts sectioned separated from each other, and the parts shown being on a larger scale than in the other views.

The body of the corset is made up of a back section 5 and front sections 6. The 40 back and front sections, at their upper portions, are united, approximately to the waist line, but below the waist line, they are separated so as to provide for adjustment between their adjacent edges, and such adjustment is provided for by lacings 7 applied to their lower edges, as best shown in Fig. 3. The gaps between the separated edges of the 45 front and back sections are adapted to be spanned by inner side tongue flaps 8 extended, preferably from the back section 5. Secured to the rear edges of the front sections 6 above the lacings 7, are several, as shown, two, strong adjusting tabs 9. These 50 tabs 9 are preferably made of the same material as the corset sections 5 and 6, made double and stitched firmly together, and pro-

vided at their extended edges with buckles 10. The buckles 10 may be of any suitable type, but are preferably of the well known frictional type, free from sharp tongues. 60 The tabs 9 will overlap the spaces between the gaps at the sides of the corset and the buckles 10 engage the ends of strong adjusting straps 11, the intermediate portions of which are stitched, or otherwise secured to 65 the back of the corset. The upper strap 11 is preferably two or three inches below the waist line, while the lower strap 11 is about three or four inches lower down.

Both the back and the front sections of 70 the corset will, of course, be stiffened in the customary way by suitable corset stays, certain of which will be at the adjacent edges of the sections 5 and 6. The front sections 6 are connected by a front lacing 12 and adjacent to said lacing one of the front sections is provided with the ordinary clasps or 75 separable fastenings 13, as customarily used in front laced corsets. The numeral 14 indicates a shield for lacing 12 arranged and 80 operating in the customary way.

The numeral 15 indicates front hose supporting straps attached to the lower front portions of the front corset sections 6, and the numeral 16 indicates similar hose supporting straps attached to the lower portion of the back section 5. The numeral 17 indicates outer side hose supporting straps provided, each on its intermediate portion with a suitable fastener 17a. The upper ends of 90 the straps 17 are attached to the lower adjacent portions of the back and front sections of the corset, in such manner that downward strains of the straps 17 will tend to pull together the lower adjacent portions 95 of the back and front sections of the corset.

It will be noted by reference particularly to Figs. 1 and 2, that the front corset sections 6 are "cupped" to fit a fleshy person, but to fit a slender person it will be flattened. 100 The front sections 6 are preferably given considerable increased depth, or brought lower down toward the front of the corset, so as to better support fleshy abdomens.

This corset can be used for supporting or 105 reducing fleshy abdomens, but is also serviceable for holding in position or replacing various organs. By tightening of the straps 11, the weight of the abdomen may be supported by said straps and carried from the 110 back of the wearer, without, however, applying the strain to any one part of the

back, but, on the contrary, distributing the same throughout the back section of the garment, and hence, over the hips. As the lacing 7 is below the direct line of strain from the straps, it gives an independent adjustment or gathering of the extreme lower portion of the corset and affords means for varying the "cupping" of the front of the corset. The lacings 7 will be, 10 preferably, strong elastic lacings, so that some elasticity is given to the lower portion of the corset. With the above arrangement, attention is also called to the fact that the abdominal supporting strain is also distributed throughout the front members of 15 the corset and is not applied at any one point or on any one line, as would be the case if straps were carried to the front portions of the front sections 6 of the corset. 20 Moreover, the appearance of the front of the corset is not changed or defaced.

To sum up, it may be stated, that this improved corset serves all of the purposes of an ordinary corset, and, in addition thereto, 25 affords an abdominal support, by which abdominal reductions may be made by proper adjustments from time to time, and also, is capable of such adjustments as are required for surgical purposes to hold in 30 position or to assist in repositioning displaced organs.

What I claim is:

1. A corset of the kind described comprising back and front sections connected 35 at their upper portions but with gaps between the edges thereof at the sides of the corset adjacent the bottom thereof, said front sections being separately connected and provided with a lacing at the front of 40 the corset, upper and lower tabs attached directly to the side edges of said front sections and spanning said side gaps and overlapping the side edges of the back section, and upper and lower straps intermediately 45 attached to and extended across said back section and adjustably connected to said tabs.

2. A corset of the kind described comprising back and front sections connected 50 at their upper portions but with gaps between the lower edge portions thereof at the sides of the corset, said front sections being separately connected and provided with a lacing at the front of the corset, upper and 55 lower tabs attached directly to the side edges of said front sections and spanning said side gaps and overlapping the side edges of the back section, upper and lower straps intermediately attached to and extended across said back section and adjustably 60 connected to said tabs, and lacings con-

necting the lower side edges of said front and back sections at points below the lower tabs.

3. A corset of the kind described comprising back and front sections connected at their upper portions but with gaps between the edges thereof at the sides of the corset, said front sections being separately connected and provided with a lacing at the 65 front of the corset, upper and lower tabs attached directly to the side edges of said front sections and spanning said side gaps and overlapping the side edges of the back section, upper and lower straps intermediately attached to and extended across said back section and adjustably connected to said tabs, lacings connecting the lower side edges of said front and back sections at 70 points below the lower tabs, and hose supporting straps provided at their intermediate portions with hose fasteners and each having an end attached to the lower edge of a front section and another edge attached to the lower edge of the back section. 80

4. A corset of the kind described comprising back and front sections connected at their upper portions but with gaps between the edges thereof at the sides of the corset adjacent the bottom thereof, said front sections being separately connected and provided with a lacing at the front of the corset, upper and lower tabs attached directly to the side edges of said front sections and spanning said side gaps and overlapping 95 the side edges of the back section, upper and lower straps intermediately attached to and extended across said back section and adjustably connected to said tabs, and tongues applied to the rear edges of the front sections, spanning the said side gaps and interlapped with the side edges of said back section. 100

5. A corset of the kind described comprising back and front sections connected 105 above the waist portion thereof but having gaps therebetween below said waist portion, means adjacent the bottom edges of said sections for adjustably securing the same together, said side sections having a 110 plurality of tabs secured thereto above said means spanning said gaps, and straps extended across the back section and adapted to have their ends adjustably connected to said tabs. 115

In testimony whereof I affix my signature in presence of two witnesses.

EMMA BOOBAR.
